INVENTOR:
RALPH CORSON
BY
Louis Decho
ATTORNEY

UNITED STATES PATENT OFFICE

RALPH CORSON, OF ASHLAND, NEW JERSEY

INDICATING DEVICE

Application filed May 26, 1932. Serial No. 613,658.

My invention relates to an indicating device adapted to be used with fire buckets and other liquid containers for visually indicating the level of the liquid in such receptacles.

One of the objects of my invention is to provide a simple yet reliable means of easily determining the quantity of water in such containers as fire buckets in factories, on ships and in large buildings where the water in the buckets is continuously evaporating and where only a periodic inspection is held.

Another object of my invention is to provide a means of determining the quantity of liquid in a container, such as a fire bucket, which is readily detachable from the bucket and which in no way impairs the efficiency of the function of the bucket in an emergency.

An additional object of my invention is to facilitate the inspection of containers of liquids in that containers not readily accessible can be reliably checked at a considerable visual distance.

A further object of my invention is to provide an indicating device so reliable in operation that its use will be extended to the further enhancement of safety measures and so simple in construction that its manufacture is inexpensive and its permanence of certain action indefinitely prolonged.

Additional features and advantages of the construction of the device will more fully appear in the specification in connection with the accompanying drawing, in which:

35 Figure 1 is a perspective view of the indicating device with the visual indicator "full" in observable position.

Figure 2 is a vertical sectional view of the indicating device shown attached to a water fire bucket.

Figure 3 is a front elevational view of the device with the visual indicator "low" in observable position.

40 Figure 4 is a rear elevational view of the device in the position shown in Figure 3.

For the purpose of illustrating my invention, I have shown in the accompanying drawing one form thereof which is at present preferred by me, since the same has been 45 found in practice to give satisfactory and

reliable results, although it is to be understood that the various instrumentalities of which my invention consists can be variously arranged and organized and that my invention is not limited to the precise arrangement and organization of the instrumentalities as herein shown and described.

In the drawing wherein similar numerals of reference indicate corresponding parts in the drawing, 1 designates a fire bucket on the rim of which the device is suspended by the hook 2. The hook 2 is formed on the upper end of the wall 3 which is bent into a U shape as at 4 and terminates in the spaced vertical limbs 5 and 6. The vertical limbs 5 and 6 project beyond the rim of the bucket and carry the plate 7 on which is inscribed the word "low". To one of the vertical limbs 5 or 6 is slidably attached the float 8 by means of the guide 9. The guide 9 to which the float 8 is rigidly attached moves freely in a vertical, rectilinear manner on the limb to which it is attached. A plate 10 has inscribed on it the word "full" and is rigidly attached to the float 8 and moves freely with the float 8 on the limbs 5 and 6 by means of the guides 11 and 12.

The manner of operating the device described in Figures 1 to 4 is briefly as follows:

Assuming that the water in the bucket 1 is low, the float 8 descends with it on the limbs 5 or 6 and carries with it the plate 10 on which the word "full" is inscribed, thus causing the latter to disappear behind the wall of the bucket. The float 8 and the plate 10 are constrained to a truly vertical rectilinear motion by means of the guides 9, 11 and 12. When the plate 10 has thus descended into the bucket 1 the wall 7 on which the word "low" is inscribed is exposed to visual observation. In Figure 2 the range of movement of the float is represented from its lower position at 8 to its upper position at 8'. When the bucket is replenished with water the float 8 rises carrying the plate 10 with it to conceal the word "low" on the plate 7 and to expose the word "full".

I am aware that the invention may be embodied in other specific forms without departing from the spirit or the essential at-

tributes thereof, and I therefore desire the present embodiment to be considered in all respects as illustrative and not restrictive, reference being had to the appended claims 5 rather than to the foregoing description to indicate the scope of the invention.

Having thus described my invention, what I claim as new and desire to secure by Letters Patent is:

- 10 1. An indicating device comprising a vertical arm adapted to be secured within a container, the upper end of said arm extending above the rim of said bucket and bearing any desired indicia, a float slidable on said 15 arm, a shield carried by said float and bearing other indicia, whereby the indicia on the upper end of said arm are alternately concealed and exposed by the rise and the fall of said float owing to the rise and the fall of 20 the liquid in said container.
2. A device for indicating the level of a liquid in a container comprising a substantially U-shaped bracket adapted to be secured to the rim of and to extend downwardly into said container, a float slidable on one of the limbs of said U-shaped bracket, the upper rim of said limb projecting above the rim of said container and bearing any desired indicia, and a shield carried by and 25 slidable with said float and bearing other indicia, whereby the indicia on the upper end of said limb is alternately concealed and exposed by the rise and the fall of said float owing to the rise and the fall of the liquid in 30 said container.
- 35

In testimony whereof, I affix my signature.
RALPH CORSON.
